United States Patent Office.

ELIJAH YOUNGS, OF TUSCARORA, NEW YORK.

Letters Patent No. 80,794, dated August 4, 1868.

IMPROVED MOP AND CLOTHES-WRINGER.

The Schedule referred to in these Letters Patent and making part of the same.

TO ALL WHOM IT MAY CONCERN:

Be it known that I, ELIJAH YOUNGS, of Tuscarora, in the county of Livingston, and State of New York, have invented a new and useful Improvement in Mop and Clothes-Wringers; and I do hereby declare the following to be a full, clear, and exact description of the same, reference being had to the accompanying drawings, in which—

Figure 1 is a perspective view of my wringer applied to a common pail for the purposes of a mop-wringer.

Figure 2 is a side elevation of the same.

Figure 3 is a plan of the same, to show a preferable arrangement of the pressure-levers.

Figure 4 is an elevation of the ear and its socket-plate.

Figure 5 is an elevation and cross-section of socket-plate.

Figure 6 is an elevation of cam-buttons.

My invention relates to that class of wringers in which the rollers are pressed toward each other by means of a treadle, upon which is placed the foot of the attendant, and it consists in the mode of mounting the various parts so that they may be readily attached to a common pail without subjecting the same to undue strain during the time of operation.

My invention is equally adapted to the wringing of clothes or mops, and is especially useful in the wringing of such articles as bed-quilts, sheets, &c. The only changes required to adapt the device to the one or the other purpose is in the form of the ears or supports, in which the rollers have their bearings to make said ears or lugs conform properly to the larger or smaller diameter of a tub or pail, without destroying the parallelism of the bearings.

If desirable, the lugs or ears, which support the rollers, may be made readily detachable, so that the same vessel may be employed for any of the ordinary purposes for which it is adapted.

That others may fully understand my invention, I will particularly describe it.

A is the tub or pail, which serves as the receptacle for the water to be extracted from the mop or other article. This tub may be constructed in any desirable way, either with staves, in a circular form, or rectangular. To the sides of the vessel A are attached the ears or lugs B, which support the journals of the squeezing-rollers C C'.

The lugs B are made to extend a distance down the side of the vessel A sufficiently far to receive the pivot D, upon which the treadle-lever E moves.

The lever E may be made of a single bar of iron, bent in such form as will enclose the vessel A between its ends, and with its central loop projecting some little distance beyond the side of the vessel, so as to afford a convenient rest for the foot of the attendant, as shown in the figures.

The ends of the bar E are curved upward, so as to come close beside the ear or lug B on opposite sides of the vessel A respectively, and the journals of the roller C' pass through suitable holes made in the ends of said bar.

The journals of the roller C' also pass through slots F in the ears B, said slots being segments of circles struck from the centres of pivots D, so that, as the treadle-lever E is moved upon said pivots, the journals of the roller C' are carried along said slots, which act as supports and guides to aid the lever E in resisting the irregular strains incident to the passage of bodies of various thicknesses between the squeezing-rollers C C'.

The ends of the treadle-lever may be bent laterally a little, so as to cause them to pass inside of the lugs or ears B, as shown in fig. 3, by which arrangement the strains upon the journal of the roller C' are brought nearer to the ends of rollers, and there is less liability of springing the journals than if the levers are arranged outside of the ears.

The treadle E may, of course, be made of other material than iron, and need not necessarily be made in one piece, and the ears or lugs B may likewise be made of wood or iron, as may by different persons be deemed preferable; the only essential requisites being that the curved slot F should be a segment of a circle drawn about the centre, upon which the treadle moves, and that the ends of the said treadle, which bear the journals of the roller C', should move in arcs of the same circle.

To make the wringing-device easily removable from the vessel A, a variety of devices may be employed; as, for instance, suitable lugs, or other stops, may be secured to the side of the pail to prevent lateral movements of the ear when in position, and said ear may be firmly retained in place by an eye and pin. But a fastening which I have devised, and which I will now describe, I prefer to all of the usual expedients adopted in similar cases.

The ear is made so that its lower end fits within the flanged edge of a plate, G, which thus forms a seat or socket enclosing the edge of the lower part of the ear B, or that part of the same which laps over the side of the vessel A. The edge of the ear B may be bevelled, and the flange of the plate G may be made correspondingly inclined, so as to form a dove-tailed recess for the ear B. The central portion of the ear B is made open, and to that part of the plate G which is exposed by the opening through the ear, may be secured a cam-button, H, which is so shaped that when it is turned up the ear may be withdrawn from its socket, but when it is turned down, it will press against the edge of the ear and force it into its seat in the socket of the plate G, the cam-surface of button then acting with the necessary power to force the ear home, and to retain it rigidly in place.

The plate G may be permanently attached to the pail or tub, and will not be in anywise objectionable in any use for which the pail or tub may be required. If it should be deemed desirable by any person to have the wringing-device permanently attached, the ear B may be screwed directly to the vessel, and the socket-plate G dispensed with.

The foot-piece I may be used upon pails for the purpose of applying one of the feet to steady the pail while drawing the mop or article of clothing between the rollers.

To insert the mop between the rollers, the lever E is raised with the toe, and the mop inserted. The foot is then placed upon the lever E, and the requisite pressure brought upon the rollers as the mop is withdrawn. The operation in regard to the other articles is the same.

By the use of the ears B, the strain of squeezing a mop or other article is not imposed upon the hoops and staves of the pail to so large a degree as when the common methods are adopted, and it will be found very desirable to be able readily to remove the wringer from the vessel to which it must be attached while in operation.

The method of producing the proper pressure by the foot is very desirable, because the amount of pressure can then be always and instantly regulated by the operator. The curved slot F enables me to employ a much lighter lever than would otherwise be the case, as it supports and regulates the movements of the rollers to or from each other.

Having described my invention, what I claim as new, is—

1. The ear B, provided with the slot F, curved as described and for the purpose set forth.
2. The combination of the ears B B, provided with slots F F, curved as described, with the rollers C C', and the lever E, substantially as and for the purpose set forth.
3. The socket-plate G, provided with a cam-button, H, or its equivalent, in combination with the ear B, substantially as and for the purpose set forth.
